(57) **CLAIM**

I claim the ornamental design for a mounting clamp, as shown and described.

DESCRIPTION

FIG. 1 is a top plan view thereof.

FIG. 2 is a front elevation view thereof.

FIG. 3 is a right side elevation view thereof. The left side being a mirror image.

FIG. 4 is a bottom plan view thereof.

FIG. 5 is a back elevation view thereof; and,

FIG. 6 is an isometric view of the mounting clamp, wherein the broken line disclosure is for illustrative purposes only and forms no part of the claimed design.
